UNITED STATES PATENT OFFICE.

WILLIAM A. HASTINGS, OF SAN FRANCISCO, AND NEAL J. HARRINGTON, OF OAKLAND, CALIFORNIA, ASSIGNORS TO GEO. W. CASWELL COMPANY, OF SAN FRANCISCO, CALIFORNIA, A CORPORATION OF CALIFORNIA.

APPARATUS FOR CLEANING COFFEE-BERRIES.

SPECIFICATION forming part of Letters Patent No. 700,327, dated May 20, 1902.

Application filed January 14, 1901. Serial No. 43,167. (No model.)

To all whom it may concern:

Be it known that we, WILLIAM A. HASTINGS, residing in the city and county of San Francisco, and NEAL J. HARRINGTON, residing at 5 Oakland, county of Alameda, State of California, citizens of the United States, have invented certain new and useful Improvements in Apparatus for Cleaning Coffee-Berries; and we do hereby declare the following to be a

10 full, clear, and exact description of the same.

The present invention has for its object the production of an apparatus by means of which the silk skin or enveloping covering for the berry may be removed without injury to the berry, and this at an expense not exceeding 15 that at present required in order to polish the berry preparatory to placing the same upon the market. In addition to the removal of the silk skin the present apparatus removes 20 dirt or foreign matter adhering to the berry, and likewise polishes the same. Consequently after treatment of the berries by the herein-after-described apparatus it is not required 25 that the berries be subjected to the ordinary polishing process.

In order to comprehend the invention, reference should be had to the accompanying sheet of drawings, forming a portion of the present application, wherein—

30 Figure 1 is a front view in elevation of the apparatus, partly broken away; and Fig. 2 is an end view in elevation viewed from the feed end of the apparatus.

The letter A is used to indicate any suitable 35 style of frame, within bearings a and a' of which work, respectively, the upper and lower shafts A' and A^2 . The shaft A^2 supports a cylinder, drum, or casing B, which casing is loosely mounted thereon. The casing is preferably composed of reticulated material, although, if so desired, it may consist of perforated sheet metal. Said casing or cylinder is provided with the bearing-rings B' B^2 , the former of which is united to the head B^3 for 40 one end of the cylinder or casing. These bearing-rings rest upon the supporting-rolls C, two for each end of the cylinder or casing, and bearing-ring or circular flange B' is provided with internal gear-teeth b . Consequently the same may properly be termed an

“internal” gear-ring. The opposite bearing-ring works against the inner face of the fixed head C', which head is held against movement by latch d , supported by the fixed bracket C², secured to the frame A, Fig. 1. 55

To the upper shaft A' is secured the cylinder or casing D, which cylinder or casing we term the “mixing-cylinder.” This cylinder or casing is a solid one and revolves with the shaft A', which shaft is driven from any suitable machinery by means of a belt passing over belt-wheel D'. To this shaft is also secured belt-wheel D², which is connected with belt-wheel D³ by means of belt D⁴. By this connection the motion of shaft A' is transmitted to short shaft E, to which the belt-wheel D³ is secured. To the opposite end of this shaft is secured a pinion d', which pinion meshes with the internal teeth b of the gear-ring B'. By this manner of connection the motion of shaft A' is transmitted to the lower cylinder or casing B. 60 65 70

The lower shaft A² is driven from any suitable source of power by means of a power-belt (not shown) working over belt-wheel E', secured to one end of said shaft. This shaft has imparted thereto an opposite rotation to that given to the cylinder or casing B. To that portion of the shaft A² within the separating cylinder or casing B is secured a series 75 80 of knobs or projections d'', which answer as fingers for stirring the material fed therein during the rotation of the said shaft and cylinder.

The head E² of the mixing cylinder or casing is a non-rotating one, against which the open end of the cylinder or casing bears. This head is held against rotation in the same manner as head C—that is, by means of a catch d⁵, which engages with lug d⁶, projecting from the head. The catch d⁵ works through fixed bracket E³, projecting from the frame A. The lower catch d engages with lug d⁴, projecting from head C'. 85 90 95

Into the mixing cylinder or casing D, through head E², leads the feed-chute F, and into separating-cylinder B, through head C', leads the chute F', Fig. 1 of the drawings.

The inner wall of the mixing chamber or casing D is provided with a series of spiral- 100

shaped blades F^2 and the inner wall of the separating-chamber with a similar series of blades F^3 . These blades during the rotation of the cylinders serve to raise the material fed therein and to work the same.

The material to be treated—that is, the coffee-berries—is fed into the upper or mixing cylinder or casing and water introduced into the same, after which a quantity of powdered absorbent is introduced to take up the undue moisture. During the rotation of the mixing cylinder or casing the material is thoroughly intermixed, after which the catch d^3 is released and the head E^2 turned upon the shaft A' , so as to place the chute F over chute F' . When in this position, the catch is moved inward, so as to again engage with lug d^3 and hold the head E^2 against movement. As the mixing cylinder or casing continues its rotation the material therein will be gradually forced into the chute F by the spiral blades F^2 , which act as a worm conveyer. As delivered to the chute F the material will pass through chute F' into the separating cylinder or casing B . Inasmuch as the cylinder or casing B and shaft A^2 are driven in opposite directions the material fed therein will be thoroughly ground together and the silk skin or covering of the coffee-berry previously loosened by moisture will by attrition be removed from the berries, likewise any foreign substance or dirt. The material released from the berries will by centrifugal force be discharged from the separating cylinder or casing through the outlet openings in its foraminated body, while the friction caused by the rapid stirring of the berries, together with the air drawn into the cylinder or casing, will answer to perfectly dry the berries. This rapid stirring of the berries within the separating cylinder or casing not only answers to perfectly clean the berries; but the frictional contact of the berries serves to highly polish the same. After the berries have been treated in the separating-cylinder for about half an hour or sufficient time in which to clean same the latch d is released and the head C' turned over, so as to place chute F' below the cylinder or cas-

ing. When the chute stands in this position, the berries will be gradually forced therein by the worm conveyers or blades during the continued rotation of the cylinder or casing and discharged into any suitable receptacle for this purpose.

Having thus described our invention, what we claim as new, and desire to secure protection in by Letters Patent, is—

1. The combination with a mixing-cylinder, of a separating-cylinder, means for imparting rotation to said cylinders, a rotatable head for each cylinder capable of movement independently of the cylinder, a spout carried by each head adapted to be adjusted therewith to discharge material from the mixing-cylinder into the separating-cylinder, and means for holding the heads against movement, substantially as described.

2. In combination substantially as described a mixing-cylinder, means for rotating the same, a separating-cylinder adjacent to the mixing-cylinder, a head formed with an internal gear-ring at one end of the separating-cylinder, gearing between said head and mixing-cylinder, the rotating means for the mixing-cylinder adapted to simultaneously rotate the separating-cylinder, and an independently-rotatable head at the free end of the separating-cylinder adapted to be adjusted to afford an inlet and an outlet for the material to be treated, substantially as described.

3. In combination substantially as described, a mixer and a separator located therebeneath, independently - rotatable heads at adjacent ends of said mixer and separator arranged in substantial alinement, and spouts on the heads adapted to be adjusted therewith to discharge material from the mixer into the separator.

In witness whereof we have hereunto set our hands.

WILLIAM A. HASTINGS.
NEAL J. HARRINGTON.
